KNOT TIER

Wilbur W. Ellenbecker, Appleton, Wis.

Application December 16, 1940, Serial No. 370,406

1 Claim. (Cl. 289—17)

This invention relates to knotting devices and more particularly to a manually operable device of improved and simplified structure, by means of which string may be rapidly and efficiently knotted around the folded ends of bologna, and the like.

The object of the invention is to provide means by which an operator can utilize a foot and supply substantially uniform knotting pressure while being relieved of the necessity for applying such procedure with his hands, which necessarily become greasy and slippery in connection with handling such objects.

Various other objects will suggest themselves in the course of the following detailed description.

The invention consists in the novel construction, arrangement, and combinations of parts hereinafter more specifically described and claimed.

One sheet of drawings accompanies this specification as part thereof, in which like reference numerals indicate like parts throughout.

In the drawing Figure 1 is a side elevation of the improved device;

Figure 2 is a front view of the device;

Figure 3 is a fragmentary perspective illustrating the use of the device.

The particular embodiment of the invention illustrated shows a base 1 adapted to be secured to any suitable table, upon which are pivotally mounted as by bolts 12 two spaced vertically extending levers 11—11, one of which is provided near its upper free end with a through guide hole 16 through which the string S to be used in the device is threaded while the upper end of the opposed lever 11 is provided with a slot 17 also adapted to receive this string. The base 1 is provided with a central hole and bushing 2 within which is slidably positioned a rod 3 pivoted at its lower end as by bolt 4 to a pedal lever 5 pivoted at its rear end as by bolt 6 to an angle plate 7 adapted to be secured to the floor. The rod 3 is provided with a screw eye 8 positioned below base 1 and this screw eye 8 is connected as by spring 9 to a second screw eye 10 supported from base 1. It will be apparent that the spring 9 will tend normally to raise rod 3 with respect to the base and elevate foot pedal 5. The upper end of rod 3 is bent laterally as at 15 and upon

it are pivoted two links 13—13 which are pivoted respectively as by bolts 14—14 to the spaced levers 11—11. Near the upper end of the lever 11 which has its upper end provided with the slot 17 is secured a knife 18 conveniently positioned for severing the knotted cord upon the completion of the knotting operation. The base 1 also carries an upwardly directed spindle 19 adapted to receive a cone of cord 20 and from which the string S is conveniently guided through the guide hole 16 in the adjacent lever 11 and thence through the slot 17 in the opposed lever 11.

In operation the string S having been threaded through the hole 16 is cast in a single loop 21 around the free end of that lever to prevent further feeding of the string therethrough. The free end of the string is then passed into slot 17 and cast in oppositely directed small loops e—e' around the folded end of the casing of the bologna. These loops should be cast as suggested in opposite directions to provide the effective knot commonly known as a "half-hitch." Pressure of the foot on the foot pedal 5 will depress rod 3 and links 13—13, thus forcing levers 11—11 apart and drawing the string S taut with uniform pressure on the doubled loops cast on the bologna casing. The pedal being released the levers 11—11 again draw together thus permitting the lowering of bologna to cut the string on knife 18 and the operation can be repeated with great rapidity and precision.

Various modifications in the precise construction and arrangement of the parts will readily suggest themselves to those skilled in this art but all within the scope of the present invention as claimed.

Having thus fully described my invention I claim:

A knot tightener comprising a base, two spaced members pivoted at their lower ends to the base and having their upper ends formed with string guiding means, a rod vertically slidable through the base, links connecting the upper end of the rod with said spaced pivoted members, spring means connecting the rod and base to normally elevate the rod and rock the spaced members towards each other, and pedal means for depressing the rod.

WILBUR W. ELLENBECKER.
